(57) **CLAIM**

The ornamental design for a bottle opener with knife sharpener, as shown and described.

DESCRIPTION

FIG. 1 is a perspective view of a bottle opener with knife sharpener showing our new ornamental design;

FIG. 2 is a front view thereof;

FIG. 3 is an inverted rear view thereof;

FIG. 4 is a bottom plan view thereof;

FIG. 5 is a top plan view thereof;

FIG. 6 is a right side elevational view thereof rotated 90 degrees; and,

FIG. 7 is a left side elevational view thereof also rotated 90 degrees.

The present invention relates to an ornamental design for bottle opener that can also be used for knife sharpening.
